DESIGN FOR A DOOR CLOSER

Hiram Benjamin Gallinger, Superior, Wis.

Application April 17, 1939, Serial No. 84,352

Term of patent 14 years

To all whom it may concern:

Be it known that I, Hiram Benjamin Gallinger, a citizen of the United States and a resident of Superior, in the county of Douglas and State of Wisconsin, have invented a new, original, and ornamental Design for a Door Closer, of which the following is a specification, reference being had to the accompanying drawing, forming part thereof.

In the drawing:

I claim:

The ornamental design for a door closer, as shown.

HIRAM BENJAMIN GALLINGER.
